UNITED STATES PATENT OFFICE.

VICTOR C. VAN'T WOUD, OF BROOKLYN, NEW YORK.

DESIGN FOR A HOT-WATER BAG OR SIMILAR ARTICLE.

SPECIFICATION forming part of Design No. 36,172, dated December 16, 1902.

Application filed October 30, 1902. Serial No. 129,488. Term of patent 7 years.

To all whom it may concern:

Be it known that I, VICTOR C. VAN'T WOUD, a citizen of the United States, residing at Brooklyn, in the county of Kings and State of New York, have invented and produced a new, original, and ornamental Design for Hot-Water Bags or Similar Articles, of which the following is a specification, reference being had to the accompanying drawings, forming 10 a part thereof.

My invention consists of a new and original design for hot-water bags and similar articles, said articles being usually made of rubber; and it consists in the novel features 15 hereinafter set forth and described, reference being had to the accompanying drawing.

The drawing represents a plan view of a hot-water bag or reservoir of a general ovi- 20 ate form and having a thickened edge and provided with my new design.

As shown in the drawing, my design consists in a series of beads A, extending longitudinally of the bag, said beads having the 25 appearance of being corded, and also in a series of groups of fine ribs B, which extend longitudinally and are substantially parallel to the corded beads. Between the beads and the outer ribs of each group of ribs, and extending obliquely in substantially opposite 30 directions are shorter fine ribs C.

It is obvious that this design may be used on many articles similar to the one on which I have shown it, such as fountain-syringes and the like, and it is also obvious that it 35 may be applied to articles of different conformations.

Having described my invention, what I claim as new, and desire to secure by Letters Patent, is—40 The ornamental design for a hot-water bag or similar article as herein shown and described.

In testimony whereof I affix my signature in presence of two witnesses.

VICTOR C. VAN'T WOUD.
